Setting Slatin

The undersigned are joined to in these Slatin Slatin and making part of the same, retaining a description in the words of the said S. has et Howard & Caleb Howard themselves of their improvement in the Slatin machine.

It is to be known these presents shall come to T. B. C. it is known that we Siba Howard of Easton in the County of Bristol in the State of Massachusetts and Caleb Howard of West Bristol in the County of Plymouth in which state have invented a new and useful improvement in the mode of placing boards in the Slatin machine so that the Slatin are completed at one operation and the following is as full and exact description thereof. The upright saw board is hung or fixed in the novel way. Our improvement consists in placing within board behind the upright saw one or more horizontal circular saws to be driven by a belt from the upright saw shaft, otherwise. These horizontal saws are fixed upon a perpendicular shaft having an upright frame at such distance from each other as may be necessary to saw the boards of the necessary width or thickness. These distances may be varied by increasing or diminishing the thickness of the board, which is placed upon the shaft between them and they may be caused to have them saw the edge when the upright saw cuts the side of the board or vice versa. We claim as our invention the application of one or more horizontal saws so placed that boards may be sawed from a block of wood in one operation as described above. We make the large upright saw about thirty inches in diameter and the horizontal saws about seven inches in diameter. The frame upon which the block from which the boards are to be made is fastened is moved up toward the saw the width or thickness of a Slat each time the carriage returns to first position by a neck and falling dogs in the usual way. The width of the Slat is varied so that the Slat may be sawed edgewise or flatwise as may be desired. We claim as the first of this machine than the horizontal circular saws and the fixtures necessary for their operation as described above by which the Slat may be made complete at one operation. In testimony that the above

15. The application of the above principles has resulted in a
16. more rapid development of the 13th day of November 1934.
